UNITED STATES PATENT OFFICE.

WILLIAM H. NUTT, OF NEWBURYPORT, MASSACHUSETTS.

DESIGN FOR A SHOE HEEL.

Application filed January 17, 1923. Serial No. 4,909. Term of patent 7 years.

To all whom it may concern:

Be it known that I, WILLIAM H. NUTT, a citizen of the United States, residing at Newburyport, in the county of Essex and State of Massachusetts, have invented a new, original, and ornamental Design for a Shoe Heel, of which the following is a specification, reference being had to the accompanying drawings, forming a part thereof.

In the drawings:

Fig. 1 is a side elevation of a heel embodying my new design.

Fig. 2 is a rear elevation.

Fig. 3 is a bottom plan view.

Fig. 4 is a section on line 4—4, Fig. 1.

My new design comprises a series of upwardly flaring depressions extending from the bottom portion to the top portion and arranged around the rounded outer portion of the heel, said depressions being concaved transversely, said depressed portions being separated from each other by thin edged ribs.

What I claim is—

The ornamental design for a shoe heel, as shown and described.

WILLIAM H. NUTT.
